UNITED STATES PATENT OFFICE.

CORNELIUS J. NOLAN, OF TOLEDO, OHIO, ASSIGNOR TO THE LIBBEY GLASS COMPANY, OF TOLEDO, OHIO, A CORPORATION OF OHIO.

ART OF FIRE-POLISHING GLASS.

SPECIFICATION forming part of Letters Patent No. 766,514, dated August 2, 1904.

Application filed April 25, 1904. Serial No. 204,874. (No model.)

To all whom it may concern:

Be it known that I, CORMELIUS J. NOLAN, a citizen of the United States, residing at Toledo, in the county of Lucas and State of Ohio, have invented certain new and useful Improvements in the Art of Fire-Polishing Glass, of which the following is a specification.

My invention relates to improvements in the art of polishing a glass surface so as to remove marks and other imperfections therefrom and leave the same in a finished condition by softening such surface of the glass by the application of fire.

The object of my invention is to so improve this art that an article, particularly pressed-glass articles and blanks for cut glass, may be cheaply and rapidly fire-polished while at the same time retaining their shape and avoiding all possibility of chipping or otherwise marring the articles being so polished. This and such other objects as may hereinafter appear are attained by my improvement in this art, which improvement may be conveniently practiced with the apparatus shown in the accompanying drawings, in which—

Figure 1 is a plan view of a convenient form of apparatus for practicing my improved process. Fig. 2 is a side elevation of the same apparatus. Fig. 3 is an end elevation of the same, and Fig. 4 is a plan view of the motor-wheel.

Like letters of reference indicate the same parts in the several figures of the drawings.

Referring by letter to the accompanying drawings, A indicates the top of a portable table or stand, which is supported upon the legs B and the wheels or rollers C. Mounted within the table-top A is a rotatable plate D, which is carried upon a spindle E, the spindle E being journaled in the bottom of the frame of the apparatus at e and being provided with convenient means for its rotation, such means, as illustrated in the drawings, consisting of an air motor or wheel F, which is adapted to be operated by an air-blast from the nozzle G.

H is a gas-burner to which gas may be supplied through the pipe J and an air-blast through the pipe K, the gas-burner being car-

ried upon the arm L, upon which is formed a sleeve l, which is angularly adjustable or rotatable upon a sleeve M and is supported in position by a collar m. The sleeve M is mounted upon a standard N' and is provided with an adjusting-screw N, which has screw-threaded engagement with the sleeve M and which abuts against or rests upon the top of the standard N'. The screw-threaded shaft N is provided with a hand-wheel n, by means of which it may be rotated.

O O are nozzles through which blasts of cold air may be projected against the glass article or blank P, which is mounted upon the rotatable plate or disk D.

With this explanation of the construction of the apparatus I will explain my process. The blank P, as shown, may be taken as typical of any article of pressed glassware or of a pressed blank to be subsequently cut in the usual manner to form a cut-glass article. The blank P having been pressed in the usual manner will bear upon its inner face various lines and imperfections arising from contact with the plunger of the mold and perhaps from other causes, which deprive it of the high polish which is desirable in the finished article. As soon as the blank has sufficiently set its shape to allow of being handled it is placed upon the rotatable plate D. The plate D is then rotated beneath the gas-burner H, which burner, it will be noted, can be adjusted both laterally and vertically to suit varying requirements.

At the same time blasts of cold air are projected against the exterior of the blank P through the nozzles O. The effect of these blasts of cold air is to keep the exterior of the blank cool, so as to prevent the exterior of the blank from coming under the influence of the gas-jet which is projected into the gas-burner H, and thus becoming distorted. While the blasts of cold air are projected against the exterior of the blank P while the blank is being rotated by the rotation of the plate D, a blast of flame is projected against the inner face of the blank P from the burner H, whereby the inner face of the blank P is softened and melted sufficiently to remove all marks and defects there-

from and to give the glass the required high polish. Thereupon the jet of flame is discontinued and the blank P is removed and cooled in the usual manner.

- 5 While I have shown and described a simple, convenient, and effective form of apparatus for carrying out my process, it will be seen that my process may be carried out in a variety of ways with different forms of apparatus without departing from the spirit of my invention, so long as the exterior of the blank is kept cool, substantially in the manner shown, while the interior of the blank is being subjected to the action of a sufficiently high degree of heat, the characteristic feature of my invention being that I preserve the form of the blank under treatment—that is, I prevent distortion of the blank by keeping the exterior of the blank sufficiently cool during the application of the heat to the inner surface, or vice versa—that is, sufficiently cool to retain its shape instead of depending upon mechanical means for supporting the plastic blank, which would otherwise become distorted under the influence of the polishing-flame. With this understanding of the fundamental characteristics of my process various methods of applying it will be readily devised by persons skilled in the art.
- 25 30 It will be noted that with the process described the handling of the article is reduced to a minimum, the possibility of chipping or breaking the exterior of the article or any figure thereon may be eliminated, there is a saving due to the fact that a minimum of labor is required, and there is also a saving due to the rapidity with which the article can be fire-polished.
- I claim—
- 40 1. An improvement in the art of fire-polishing glass, which comprises supplying a pol-

ishing heat to one surface of a glass article and simultaneously subjecting the opposite surface of the article to a cooling influence, whereby the article retains its shape during the application of the polishing heat.

2. The improvement in the art of fire-polishing glass which comprises applying a polishing heat to one surface of the glass article and simultaneously subjecting the opposite surface of the article to the action of means for keeping such surface of the article sufficiently cool to preserve the shape of the article during the application of the polishing-flame, and simultaneously rotating the article while being so treated.

3. The improvement in the art of fire-polishing glass which comprises projecting a jet of flame against one surface of the article to be polished and simultaneously projecting a cooling-jet against the opposite surface of the article to be polished so as to keep such opposite surface sufficiently cool to prevent distortion of the article under treatment.

4. The improvement in the art of fire-polishing glass, which comprises projecting heat against a rotating blank and simultaneously subjecting said blank to the action of a cooling-jet whereby the blank is caused to retain its shape while it is subjected to the action of said heat.

5. The improvement in the art of fire-polishing glass, which consists in rotating the article to be polished, projecting heat against the interior of said article during said rotation, and simultaneously projecting a cooling medium against the exterior of said article, substantially as described.

CORNELIUS J. NOLAN.
